UNITED STATES PATENT OFFICE.

AUSTIN F. JACKSON, OF TAUNTON, MASSACHUSETTS, ASSIGNOR TO REED AND BARTON CORPORATION, OF TAUNTON, MASSACHUSETTS.

DESIGN FOR A PLATTER OR SIMILAR ARTICLE.

SPECIFICATION forming part of Design No. 36,154, dated December 9, 1902.

Application filed August 18, 1902. Serial No. 120,161. Term of patent 14 years.

To all whom it may concern:

Be it known that I, AUSTIN F. JACKSON, a citizen of the United States, residing at Taunton, in the county of Bristol and Commonwealth of Massachusetts, have invented and produced a new, original, and ornamental Design for a Platter or Similar Article, of which the following is a specification, reference being had to the accompanying drawings, forming a part thereof.

Figure 1 is a plan view showing my design. Fig. 2 is a side elevation of the platter or meat-dish.

The leading or material feature of my design consists in the general contour of the article, together with the special ornamentation

(conventional design) at the ends and sides, as shown.

Having described my invention, what I claim as new, and desire to secure by Letters Patent, is—

The ornamental design for a platter, or similar article, as herein shown and described.

In testimony whereof I have signed my name to this specification, in the presence of two subscribing witnesses, on this 11th day of August, A. D. 1902.

AUSTIN F. JACKSON.
